UNITED STATES PATENT OFFICE.

GEORGE HENRY GIDDINGS, OF ILLION, NEW YORK.

EJECTING DEVICE FOR DOUBLE-BARREL GUNS.

1,309,026.

Specification of Letters Patent.

Patented July 8, 1919.

Application filed October 16, 1918. Serial No. 258,338.

To all whom it may concern:

Be it known that I, GEORGE H. GIDDINGS, a citizen of the United States, residing at Ilion, in the county of Herkimer and the State of New York, have invented certain new and useful Improvements in Ejecting Devices for Double-Barrel Guns, of which the following is a specification.

This invention relates to shell ejecting means for double barrel guns, and especially to a gun of this type shown in my application filed August 24 and bearing Serial Number 251,259, to which reference may be had for details of construction omitted from this application.

The present invention has for its object the discharge of shells from either one or both barrels, and for the preliminary starting of a shell to prevent sticking.

20 The invention also consists in the novel features of construction hereinafter described, pointed out in the claims and shown in the accompanying drawings in which:—

Figure 1 is a sectional view showing the gun in open position.

Fig. 2 is a detail sectional view showing the position occupied by the parts when the gun is only partly opened.

Fig. 3 is a section along the line of the opening, looking toward the gun muzzle, the gun being closed.

Fig. 4 is a detail plan view of a portion of the gun frame showing the ejector hammers and cocking levers.

Fig. 5 is a perspective view of one of the main hammers.

Figs. 6, 7, 8 and 9 are detail views of ejectors.

Fig. 10 is a detail side view of a pin.

40 In the drawings 1 designates the gun frame, 2 and 3 the upper and lower barrels, 4 one of the main hammers and 5 a cam carried thereby.

The ejecting devices are mounted in the gun frame on opposite sides of the concaved cut made to receive the lower barrel 3. As these parts are duplicated on opposite sides a description of one set will suffice for both, and I have more fully shown and will therefore describe the left hand set, that is the ejecting device on the left hand side of the gun looking toward the muzzle.

These consist of the following parts:

Ejector hammers 6, one on each side as in Fig. 4, ejector sears 9, springs 10, cocking

levers 11, ejectors 12 and 13; the ejector 13 being on the left hand side, ejector stop screws 14, but one of which appears in the drawings, pins 15 for the springs 10 and sear springs 16.

From the drawings it will be noted that the ejector hammers have a lower forward shoulder 7, and are recessed just to the rear of their pivotal point as at 8. There is also shown the main hammer cocking lever 17, 65 left hand side.

The main hammers carry laterally projecting pins 4^a. The right and left hand parts of the ejecting mechanism are duplicates with the exception of the ejectors 12 and 13. These comprise shank portions with heads 12^a and 13^a and there is a slight difference in the shape of the heads, the head 12^a being also the larger, to coöperate with the shell of the upper barrel.

It will be understood that if the upper barrel only is fired only the right hand ejector will eject the shell, the left hand ejector riding out to full limit of its stroke with the shell unfired and back again when the gun is closed. If the left hand mechanism only is fired, as described in the application above referred to, only the shell in the lower barrel will be ejected, but if both barrels are fired both shells will be ejected at the same time.

From Fig. 2 it will be noted that the left hand ejector hammer 6 is held in its cocked position by its sear 9, the hammer getting its striking power from the V-spring 10 which rests at one end in a cut in the frame and the other end bears on the hammer below its pivotal point. The spring is held in place at the rear end by the pin 15 which is driven laterally through the walls of the frame. The cocking of the ejector hammer is accomplished by the cocking lever 11 one end of which rides in the recess 8 of the hammer 6 and the opposite end is pressed down by contact with the water table 2^a of the barrels when the gun is closed. The sear 9 is pressed into engagement with the shoulder 7 by sear spring 16, when the hammer 6 has been pressed back a sufficient distance. To pull the sear from said shoulder at the proper moment, that is when the gun has been fully opened, the rear end portion of the sear is bent upwardly and engages the boss or pin 4^a on the main hammer 4 so that when the gun is opened and the hammer 4

is carried to full cock pin 4^a is thrown upwardly and carries the rear end of sear 9 with it, thereby drawing the opposite end of the sear away from the ejector hammer 6, as shown in Fig. 1.

This action takes place as soon as the gun is open far enough to allow empty shells to pass over the top of the frame.

When the ejector hammer 6 is released 10 by its sear 9 it strikes ejector 13, the left hand devices being described, driving the ejector out and away from the face of the barrel carrying the empty shell with it. The ejector is checked at the outward limit 15 of its movement by the stop screw 14. The heads of the ejectors are constructed so that they hook under the heads of the shells.

When the operator desires to disconnect 20 the barrels from the frame it is necessary that the ejector hammers be in uncocked position, due to the raising of the sear end by the boss 4^a. The object of this is to assure 25 that the strain is off the ejector springs when the gun is packed away in gun case thereby reducing the proportion of broken and damaged springs.

After the barrels have been disconnected 30 from the gun frame the operator can then let down the main hammers by simply pulling the trigger twice; in this way strain can be taken off all the springs in the gun when laid away in its case.

This does not make it inconvenient to disengage the barrels as the gun cocks as easily 35 with the fore-end off as it does with it on, and the cocking of gun and disengagement of the frame are both done with one movement.

In ejector devices it is necessary to have 40 a movement in advance of the final kick that causes ejection of the shells to start sticking shells, termed primary extraction. This is gained by the ejector hammers 6 taking a bearing at 18 when the gun is being 45 opened. This bearing backs up the ejector hammer and in turn forces ejector 12, or 13 as the case may be, to start the shell out of the chamber of the barrel about one eighth of an inch before ejection takes 50 place. This movement takes place when the gun is opened to a position between those shown in Figs. 1 and 2, and at such time as the barrels swinging on their pivot 55 would carry the ejector stems into alignment with the ejector hammers, or to a position approaching that shown in Fig. 1.

It is believed that from the drawings and description above given the invention will

be clearly understood and its advantages made obvious.

What I claim is:—

1. In devices of the kind described in double barrel guns, ejector hammers, slideable ejectors adapted to be struck by said hammers, stops for said ejectors, spring 65 pressed ejector hammer sears, cocking levers engaging the said hammers, V-springs engaging the cocking levers and the hammers, and main hammers adapted to engage the ejector hammer sears, and to disengage them 70 from the ejector hammers as the main hammers are drawn to full cocked position.

2. In a device of the kind described, ejector hammers pivoted in the frame on opposite sides of the barrels and having shoulders and recesses, cocking levers having their forward ends engaging said recesses, and their rear ends pressed downward by the water table when the gun is closed, 75 sears adapted to engage the ejector hammer shoulders, springs to impart striking movement to the hammers, ejecting devices in position to be struck by said hammers, main hammers controlling movement of the sears, and stops for the ejectors.

3. In ejector devices for double barrel guns, slideable ejectors arranged in the frame adjacent the barrels, stop screws limiting outward and rearward movement of the ejectors, spring actuated ejector hammers, 90 said hammers having an initial bearing on the gun frame as the gun is opened and engaging the ejectors during said opening movement thereby imparting preliminary outer movement to the ejectors, sears engaging the hammers normally and releasing them as the gun is opened, and cocking levers engaging the hammers and held, during closed position of the gun by the water table, in normal position.

4. In ejector devices for double barrel guns, ejector hammers, springs for actuating said hammers, cocking levers engaging the hammers and normally held in position by the water table of the gun, said levers 105 being released by opening of the gun, spring pressed sears engaging the hammers, said sears being disengaged from the hammers on opening of the gun, and slideable ejectors in position to be struck and forced rearward 110 by the hammers when released by the sears, as and for the purpose set forth.

In testimony whereof I have affixed my signature.

GEORGE HENRY GIDDINGS.
